(57) **CLAIM**

The ornamental design for playyard frame rail, as shown and described.

DESCRIPTION

FIG. 1 is a perspective view of an embodiment of a playyard frame rail in accordance with the present invention;

FIG. 2 is a fragmentary perspective view of the design shown in FIG. 1;

FIG. 3 is a fragmentary perspective view of the top portion of the design shown in FIG. 2;

FIG. 4 is a front elevational view of the design shown in FIG. 3;

FIG. 5 is a left side elevational view of the design shown in FIG. 3;

FIG. 6 is a right side elevational view of the design shown in FIG. 3;

FIG. 7 is a rear elevational view of the design shown in FIG. 3;

FIG. 8 is a top plan view of the design shown in FIG. 3;

FIG. 9 is a bottom plan view of the design shown in FIG. 3; and,

FIG. 10 is a top plan view of the design shown in FIG. 3, showing softgoods and decorative material arranged in the grooves of the tubing.

The broken lines illustrate environmental structure and form no part of the claimed design.
